UNITED STATES PATENT OFFICE

2,356,216

LOCOMOTIVE BOILER FIREBOX

Gust J. Christenson, Chicago, Ill., assignor to
Locomotive Firebox Company, Chicago, Ill., a
corporation of Delaware

Application September 16, 1939, Serial No. 295,240

5 Claims. (Cl. 122—68)

This invention relates to improvements in locomotive boiler fireboxes and it consists of the matters hereinafter described and more particularly pointed out in the appended claims.

One of the objects of the invention is to provide a locomotive boiler firebox including a simple and efficient means affording a better water circulating action between both side water legs and the boiler water space above the crown sheet and which means is so constructed as to brace the crown sheet and at the same time permit that amount of relative movement which occurs between the sheets of the firebox under the action of temperature changes.

Another object of the invention is to provide a locomotive boiler firebox having one or more side sheet circulators therein which may be manufactured at a relative low cost and which may be readily altered by the removal of end parts to make the same fit different sizes of fireboxes or different parts of the same firebox so that a plurality of such circulators may be installed in a longitudinally spaced relation therein.

Again, it is an object of the invention to provide a side sheet circulator made from counterpart tubes and formed at the mid portions with substantially matching mortise openings secured together in a pressure-tight relation.

The above mentioned objects of the invention, as well as others, together with the advantages thereof, will more fully appear as the specification proceeds.

In the drawing:

Fig. 1 is a longitudinal vertical sectional view through a locomotive boiler firebox embodying the preferred form of the invention, as taken on the line 1—1 of Fig. 2, with the center brick of the arch appearing in dotted lines.

Fig. 2 is a transverse vertical sectional view through a part of the firebox appearing in Fig. 1, as taken on the line 2—2 of said Fig. 1.

Fig. 3 is a detail sectional view, on an enlarged scale, as taken along the curved line 3—3 on Fig. 2, through one of the improved side sheet circulating elements embodying the invention.

Fig. 4 is a view in side elevation of one of the tubes from which the improved water steaming and circulating element, embodying the invention, is made.

Referring now in detail to that embodiment of the invention illustrated in the drawing, the firebox therein shown includes a crown sheet 10, inner side sheets 11, inner back sheet 12 and inner throat sheet 13 and flue sheet 14.

15 is the outer rear boiler sheet, 16 the outer side sheets and 17 the outer throat sheet. The said sheets cooperate with the top sheet of the boiler in forming the back water leg 18, side water legs 19 and the front throat 20 respectively, all in communication with the water space 21 of the boiler. 22 indicates the mud ring. The inner and outer back sheets are formed to provide a conventional fuel door opening as appears in Fig. 1. The foregoing may be taken as descriptive of a conventional firebox and associated parts at the rear end of a locomotive boiler.

In the firebox is located one or more water steaming and circulating elements having upper 15 portions that open through the crown sheet 10 and lower portions that open preferably through the side sheet of the firebox so as to connect the side water legs with the boiler water space above the crown sheet. The number of such elements 20 depends upon the size and type of the firebox, and as shown in Fig. 1 there are five of such elements 23, 24, 25, 26 and 27 spaced apart longitudinally and arranged transversely of the firebox.

25 Said elements are all similar in construction and differ in the length of certain of the parts thereof so that a description of one element will suffice for all. Each element is made from a pair of substantially counterpart and preferably seamless tubes 28—28, each with a straight upper end portion 29, a straight lower end portion 30 extending at an angle of more than 90° to the upper end portion and connected thereto by a longitudinally curved knee or mid portion 31. In 30 one side of the longitudinally curved portion of each tube is provided an opening 32. This opening is of a diameter approximating that of the outside diameter of the tube and has its axis spaced to one side the axis of the tube in which 35 the opening is made, as best shown by the full and dotted lines A and B in Fig. 3. Said opening cuts through one side of the tube to leave a space 33 which receives that portion 34 of the side wall of the other or companion tube in line 40 with or opposed to the space 33 of its opening.

When two of such substantially counterpart tubes are assembled together, with the edge of the opening in one tube engaged with the edge of the opening in the companion tube, they will 45 be disposed in a crossed relation and are operatively secured together in this relation by a line of welding 35 so as to form a pressure-tight mortise-like joint at this point. With such a joint connection, it is apparent that the interiors of 50 said tubes are in communication with one an-

other. If desired, those opposed portions 34 of both tubes may be tied or connected together as by a stay bolt 36.

When the tubes have been assembled as before described, they provide an element of substantially an X shape but wherein the upper end 29 of both tubes are disposed substantially upright or vertical and the lower end of said tubes diverge outwardly and downwardly from the junction of said two tubes at an angle that corresponds to the angle of lateral inclination of the arch, when such an arch is to be present in the firebox. The said ends 29 of said tubes, which function as the outlet legs for the element as a whole, are each engaged in an opening provided therefor in the crown sheet and are welded in place as at 31 to the crown sheet. The said ends 30 of said tubes which function as the inlet legs for the element as a whole, are each engaged in an opening provided therefor in the side sheets and are welded in place as at 38 preferably to diaphragms 39 in said side sheets. With this arrangement of the tubes, the axes of both tubes comprising the element are offset from each other, longitudinally of the firebox, the distance between the lines A—B before mentioned.

When an arch, as before mentioned, is present in the firebox, it is made up of transverse half rows of brick 40 that rest at their front and rear ends upon the inlet leg portions 30 of the various water steaming and circulating elements. The inner end of each transverse half row of brick terminates short of the junction of the two tubes embodied in each of such elements. This leaves a space between the inner ends of each half row of brick and this space in turn is closed by center brick 41 that rest at their side margins upon the inner end of each half row of brick.

In the operation of the boiler of which the firebox forms a part, the tubes of each element absorb heat units from the products of combustion. Due to the thermic head thus produced, water and steam are discharged through the outlet end of the tubes into the boiler water space above the crown sheet and water is drawn in from the side water legs at longitudinally spaced points along said legs. As the water passes upwardly along the inlet legs, the two streams of said legs meet at the junction or crossing of both tubes of the element, with a turbulent action, and a part of such water seeks its own outlet through the outlet legs, and the other part of said water is evaporated or generated into steam.

Thus a continuous circulatory action is established, the influence of which is exerted in all directions in the side water legs so as to there produce a turbulence which prevents the settling out of solids at the bottom of said legs. Also, due to the gushing or discharge of water from the outlet end of the tubes, a constant flooding of the crown sheet is effected which insures its complete submergence. Thus, even though the water level in the boiler falls below normal, it is assured that the same will at all times be covered with water.

The tubes, of which the elements are made, are preferably of seamless metal and may be bent to shape without cracking.

While in describing the invention, I have referred in detail to the form, arrangement and construction of the parts involved, the same is to be considered only in the illustrative sense so that I do not wish to be limited thereto except as may be specifically set forth in the appended claims.

I claim as my invention:

1. In combination with a locomotive boiler firebox including front, rear, side and crown sheets, a water steaming and circulating element in the firebox made from two separate tubes, each having a substantially upright portion that opens at one end through the crown sheet and a second portion that opens at one end through another sheet of the firebox and arranged at an angle with respect to the first portion, the other end of both portions of each tube being connected by a rounded, kneelike junction portion which has an opening therein, the junction portions of both of said tubes being disposed in crossing relation with the edges of the openings therein engaged and secured together in a pressure-tight manner and affording communication between said tubes at said junction portions.

2. In combination with a locomotive boiler firebox including side sheets and a crown sheet, a water steaming and circulating element arranged in and extending transversely of the firebox and made from two tubes, each having a substantially upright portion that opens at one end through the crown sheet and a downwardly and laterally inclined portion that opens at one end through an associated side sheet of the firebox, the other end of both portions of each tube being connected by a junction portion which has an opening therein, the two tubes intersecting each other in the firebox with the junction portions of both of said tubes being disposed in crossing relation with the edges of the openings therein engaged and secured together in a pressure-tight manner and affording communication between said tubes at said junction portions.

3. In combination with a locomotive boiler firebox including front, rear, side and crown sheets, a water steaming and circulating element in the firebox made from two tubes, each having a substantially straight upright portion that opens at one end through the crown sheet and a second portion that opens at one end through another sheet of the firebox and extends away therefrom at an inclination, the other end of both of said end portions being connected together by a curved junction portion of substantial radius and which junction portion has an opening in one side thereof at substantially its mid part, the junction portion of both of said tubes being disposed in crossing relation at said sides having the openings therein, with the edges of said openings engaged and secured together in a pressure-tight manner and affording communication between said tubes at said junction portions.

4. In combination with a locomotive boiler firebox including front, rear, side and crown sheets, a water steaming and circulating element in the firebox made from counterpart tubes, each having a straight upright portion that opens at one end through the crown sheet of the firebox and is disposed at an angle of approximately 90° with respect to said first portion, the other end of both portions of each tube being connected together by a curved junction portion which has an opening in one side thereof, the junction portions of both of said tubes being disposed in crossing relation with the edges of the openings therein engaged and secured together in a pressure-tight manner and affording communication between said tubes at said junction portions.

5. In combination with a locomotive boiler firebox including side sheets and a crown sheet, a water steaming and circulating element arranged in and extending transversely of the firebox and made from counterpart tubes, each hav-

ing a substantially straight upright portion opening at its upper end through the crown sheet and a downwardly and laterally inclined portion that opens at its lower end through the associated side sheet of the firebox, the other end of both portions of each tube being connected by a curved junction portion having an opening extending

through one side thereof, the junction portion of both of said tubes being disposed in crossing relation with the edges of the side openings therein engaged and secured together in a pressure-tight manner and affording communication between said tubes at said junction portions.

GUST J. CHRISTENSON.
